(57) **CLAIM**

The ornamental design for a device for pulling wire through conduit of electrical breaker box, as shown and described.

DESCRIPTION

FIG. 1 is a perspective view of a top, front, and right side of a device for pulling wire through conduit of electrical breaker box showing my new design with the device in an extended position;

FIG. 2 is a right side elevational view thereof;

FIG. 3 is a side elevational view of the side opposite that shown in FIG. 2;

FIG. 4 is a side elevational view taken along line 4-4 of FIG. 2;

FIG. 5 is a side elevational view taken along line 5-5 of FIG. 2;

FIG. 6 is a top plan view;

FIG. 7 is a bottom plan view;

FIG. 8 is a right side elevational view showing the upper pivoting arm in an alternate folded position; and,

FIG. 9 is a perspective view of a top, front, and right side of the device as applied to an electrical breaker box.

In FIGS. 1-9 the fastener nut shown in broken line illustrates environmental structure and forms no part of the claimed design. The broken line showing of an electrical wire and electrical breaker box in FIG. 9 is included for the purpose of showing environment and forms no part of the claimed design.
